UNITED STATES PATENT OFFICE.

PARK BENJAMIN HARVEY AND CASSIUS FREDERICK HARRIS, OF NEW LONDON, CONNECTICUT.

CURTAIN-POLE.

SPECIFICATION forming part of Letters Patent No. 555,603, dated March 3, 1896.

Application filed October 25, 1895. Serial No. 566,904. (No model.)

To all whom it may concern:

Be it known that we, PARK BENJAMIN HARVEY and CASSIUS FREDERICK HARRIS, citizens of the United States, and residents of 5 New London, in the county of New London and State of Connecticut, have invented certain new and useful Improvements in Curtain-Poles, of which the following is a specification, reference being had to the accompanying drawings, forming a part thereof, in which similar letters of reference indicate corresponding parts.

This invention relates to suspension devices for use in connection with curtain-poles 15 and for other and similar purposes, and when used in connection with curtain-poles the object thereof is to provide means for suspending a curtain, portière or other article therefrom, and with this and other objects in view 20 the invention consists in the construction, combination and arrangement of parts hereinafter described and claimed.

The invention is fully disclosed in the following specification, of which the accompanying drawings form a part, in which—

Figure 1 represents a transverse section of a curtain-pole provided with our improved suspending device; Fig. 2, a side view of a portion of said device; Fig. 3, a side view of 30 the remaining portion thereof; and Fig. 4 is a perspective view of a detail of the construction.

In the accompanying drawings, A represents a tubular curtain-pole provided with a 35 longitudinal slot or opening *a* in the bottom thereof, or in place of the curtain-pole a circularly-formed supporting device for other articles or objects may be substituted.

Mounted within the pole A is a spherical 40 body B, having a deep annular groove or recess C formed therein, which divides the ball or body into two equal parts, which are united by means of a central portion D, or the circular body or ball may be composed of two semi-circular portions united by means of a rod or 45 bolt, as will be readily understood.

Suspended from the central portion or rod D is a plate E, one end of which is preferably circular in form and provided with a bayonet-slot F, which opens at one side thereof, as 50 shown in Fig. 3, and the lower end of the

plate E is contracted to form a shank G, which projects through the longitudinal slot or opening *a* in the bottom of the pole, and at the extreme lower end of the shank G is formed a 55 hook, as shown at *g*, and formed in the body portion thereof is a vertical slot *g'*, as shown in Fig. 3, through which passes a set-screw H, by means of which the jaw K is secured to the shank G, said set-screw passing through 60 a hole *k* in the upper end of said jaw and said jaw being held in place by a nut or bur L.

The lower end of the jaw K is provided with inwardly-directed teeth or serrations M, and the operation will be readily understood from 65 the foregoing description, when taken in connection with the accompanying drawings.

The plate E is connected with the central part or rod D by being slipped thereon, as will be readily understood, in which position 70 said central part or rod D will occupy the upper annular portion *f* of the bayonet-slot, and the ball or body B is inserted into the end of the pole A, with the shank G of the plate E extending through the slot or opening *a*. In this position the jaw K may be 75 raised to the highest position on the shank G and secured thereto by means of the nut H, and when this is done the plate E cannot be removed from the ball or body B without removing the same from the pole or lowering the jaw K.

It will be understood that a curtain or other article may be clamped beneath the jaw K and the lower end of the shank G and will be 85 held in position by the teeth or serrations M on said jaw, and when the device is used for suspending or supporting curtains, portières, or similar articles a pole of any desired length may be employed, and any desired number 90 of the suspending devices may be connected therewith, and when so connected said suspending devices will be free to slide or move back and forth from one end of said pole to the other, and it will thus be seen that when 95 a curtain or portière is thus suspended the same may be moved from one end of the pole to the other, as may be desired, or extended the full length thereof.

Our invention is not limited to the exact 100 form, construction, and arrangement of parts shown and described, and we therefore re-

serve the right to make all such alterations therein and modifications thereof as fairly come within the scope of the invention.

Having fully described our invention, we 5 claim and desire to secure by Letters Patent—

In a curtain-suspending device the combination with a tubular pole having a longitudinal slot formed therein, of a spherical body 10 having a deep annular groove or recess dividing the body into two equal parts which are united by a central portion or shank, a plate suspended from said shank and having a longitudinal slot formed therein, said plate 15 having an enlarged circular end in which is formed a bayonet-slot, and a longitudinal slot formed near the center thereof, the extremity of the plate being bent into a hook, a jaw provided with inwardly-directed teeth and

having an opening in the opposite side thereof, a set-screw passing through the slot in the plate and an opening in said jaw to hold the same together, and a bur or nut upon the end of said screw whereby when the jaw is in a clamping position the jaw is parallel to 25 the shank of the plate, and the spherical body will not become detached from the clamp, substantially as described.

In testimony that we claim the foregoing as our invention we have signed our names, in 30 presence of the subscribing witnesses, this 3d day of October, 1895.

PARK BENJAMIN HARVEY.
CASSIUS FREDERICK HARRIS.
